RECEPTACLE FOR WASTE PAPER OR THE LIKE

John P. Murray, Jr., Princeton, N.J., assignor to Atlantic Products Corporation, Trenton, N.J., a corporation of New Jersey

Filed Dec. 28, 1965, Ser. No. 354

Term of patent 14 years

(Cl. D58—17)

FIGURE 1 is a front perspective view of a receptacle for waste paper or the like showing my new design;

FIGURE 2 is a rear perspective view;

FIGURE 3 is a top plan view; and

FIGURE 4 is a bottom plan view thereof.

The characteristic feature of my design, which is broadly suggestive of a golf bag, resides in the receptacle being considerably reduced in height in proportion to its width, as compared to a golf bag, and in its having at least two pockets on diametrically opposed positions on the receptacle, at least one of the pockets extending along a substantial portion of the length of the receptacle.

I claim:

The ornamental design for a receptacle for waste paper or the like, as shown and described.
